UNITED STATES PATENT OFFICE.

FREDERIC M. MILLER AND TONY J. DECKERT, OF DEMING, NEW MEXICO.

SHOW-CASE BRACKET.

1,176,588.

Specification of Letters Patent.

Patented Mar. 21, 1916.

Application filed May 21, 1915. Serial No. 29,651.

To all whom it may concern:

Be it known that we, FREDERIC M. MILLER and TONY J. DECKERT, citizens of the United States, residing at Deming, in the 5 county of Luna, State of New Mexico, have invented certain new and useful Improvements in Show-Case Brackets; and we do hereby declare the following to be a full, clear, and exact description of the invention, 10 such as will enable others skilled in the art to which it appertains, to make and use the same.

This invention relates to new and useful 15 improvements in brackets and is particularly directed to the provision of a supporting bracket for use in show cases.

It is the object of the present invention to provide such a bracket which may be placed in a show case, and which is adjustably 20 adapted to hold shelvings or to hold a plurality of rods at any desired elevation.

It is a further object of the invention to provide such a bracket which is harmonious in design and which comprises a minimum 25 number of operative parts arranged in a least conspicuous manner.

It is a more specific object in such a bracket to provide a means for holding a plurality of rods adapted to carry ribbons 30 or spools, wherein such rods are detachably held in such manner as to positively prevent any undesired displacement thereof.

With the above and other objects and advantages in view, the invention resides more 35 particularly in the combination, formation and arrangement of parts hereinafter described and specifically pointed out in the appended claim.

Reference is had to the accompanying 40 drawing wherein similar character of reference designate corresponding parts throughout the several views, and in which:

Figure 1 is a side elevation of the improved bracket. Fig. 2 is a top plan view 45 thereof, and showing a plurality of supporting rods held by the bracket. Fig. 3 is a sectional view on the line 3-3 of Fig. 1. Fig. 4 is a central vertical sectional view taken through the vertical adjusting means 50 therefor. Fig. 5 is a sectional view on the line 5-5 of Fig. 1. Fig. 6 is a perspective view of the rod holding member detached.

Referring now more particularly to the accompanying drawings, 5 designates the 55 securing strip of the bracket, to the side

edges of which are secured the edges of a pair of angular strips 6, the other edges of which are disposed over the strip in spaced relation. A supporting arm 7 is provided for the bracket, and to adjustably hold this 60 arm with relation to the structure described, the inner end of the arm is provided with the furcations 8 adapted to extend between the strips 6, and having their intermediate portions connected by a plate 9 through 65 which is loosely passed a threaded bolt 10 threadedly engaging through the central portion of a clamping plate 11. The end portions of this plate are provided with openings 12 through which slidably pass 70 the end portions of the furcations 8. This plate 11 is adapted to lie within the strips 6 and is provided on its face with a plurality of transverse teeth 13 adapted to 75 contact with a series of similar teeth 14 formed on said strips. Thus when the bolt or screw 10 is rotated to draw the clamping plate 11 against the strips 6, the ends of the furcations will be forced against the main securing strip 5, and the supporting arm will 80 be firmly held with relation to the securing strips. The position of the supporting arm may be readily adjusted by loosening the screw and sliding the securing arm to a desired position.

The outer end of the supporting arm is provided with an upstanding projection 15 which acts as a stop for any suitable shelving which may be desired to be placed thereon, and the arm is further provided with a 90 plurality of recesses 16 in its top portion for seating a number of ribbon or spool supporting rods 17. The means for holding these rods detachably in the recesses comprises a plate 18 disposed on the supporting 95 arm, and provided in its top portion with relatively wide recesses 19 alining with the recesses 16, and a finger 20 extends across the top of one side of each of said recesses 19 whereby the plate may be slid to have 100 its fingers close the upper portion of the recesses 16 and thus hold the rods in place. To mount this plate for such sliding movement, it is provided with a series of slotted openings 21, and a cover strip 22 is disposed on the plate, and has bolts 23 passed therethrough, and through the slotted openings and threadedly engaged at 24 in the support-arm. The plate is provided in its inner end with a handle lug 26 whereby it 110

may be readily manipulated. To hold the plate in extended position to close the recesses, a pawl 27 is pivoted to the inner end of the supporting arm and is adapted to swing to engage the end of the plate, a suitable stop 28 being provided on the arm to limit its swinging movement, the plate being slotted at 29 to receive said stop when the plate is retracted. Thus an exceedingly simple and compact structure has been provided for positively holding the rods with relation to the bracket.

It will be understood that a plurality of these brackets will be used in a show case, and that if desired a plurality of supporting arms may be associated with a single securing strip.

What is claimed is.

In a bracket of the class described, a supporting arm provided with rod receiving recesses in its upper edge, a plate slidable on the arm and provided with relatively wider recesses alining with the first recesses, and a finger extending from one side of each of said wider recesses, and adapted upon sliding of said plate to extend across the first recesses.

In testimony whereof, we affix our signatures, in the presence of two witnesses.

FREDERIC M. MILLER.
TONY J. DECKERT.
